United States Patent Office

Des. 222,047
Patented Sept. 28, 1971

222,047

BUILDING

Elliott H. Brenner, Lafayette, Ind., assignor to Araneida,
Inc., West Lafayette, Ind.

Filed July 17, 1970, Ser. No. 23,992

Term of patent 14 years

Int. Cl. D25—03

U.S. Cl. D13—1

FIG. 1

FIG. 2

FIG. 3

FIG. 4

FIG. 5

FIG. 6

FIG. 1 is a perspective view of a building embodying the design of the present invention;

FIG. 2 is a side-elevational view of the building of FIG. 1, the three sides of the building being identical;

FIG. 3 is a plan view of the building of FIG. 1;

FIG. 4 is a perspective view of a building constituting a second embodiment of the invention;

FIG. 5 is a side elevational view of the building of FIG. 4, the four sides being identical; and

FIG. 6 is a plan view of the building of FIG. 4.

I claim:

The ornamental design for a building, as shown and described.
